COMBINED NAPKIN HOLDER, NAPKINS, AND CONTAINER THEREFOR

Richard I. Sanger, New York, N. Y.

Application April 26, 1949, Serial No. 2,254

Term of patent 7 years

(Cl. D44—24)

To all whom it may concern:

Be it known that I, Richard I. Sanger, a citizen of the United States, residing at New York, in the county of New York, and State of New York, have invented a new, original, and ornamental Design for a Combined Napkin Holder, Napkins, and Container Therefor, of which the following is a specification, reference being had to the accompanying drawing, forming part thereof.

Fig. 1 is a rear perspective view of a combined napkin holder, napkins, and container therefor, showing my new design. The napkins are draped around the figure to illustrate their appearance at the time the article is sold.

Fig. 2 is a front perspective view showing the article removed from the container and the napkins undraped as they appear when the device is in use.

The dominant features of the design reside in the parts drawn in full lines as shown.

I claim:

The ornamental design for a combined napkin holder, napkins and container therefor, as shown and described.

RICHARD I. SANGER.
